UNITED STATES PATENT OFFICE

THOMAS WALKER FOWLER, OF WERRIBEE, AUSTRALIA

MEANS FOR USE IN ERECTING CONCRETE STRUCTURES

Application filed September 10, 1927, Serial No. 218,776, and in Australia September 25, 1926.

This invention relates to an improved method of and means for use in erecting concrete structures and refers especially to a method of and means for forming and erecting concrete wall units or slabs in the construction of buildings, walls, fences and the like.

The object of the invention is to provide a simple and efficient method of and means for forming and handling constructional units or slabs of cement or concrete whereby walls can be erected economically and expeditiously and when erected will have the same or comparatively the same stability as buildings moulded in situ.

I accomplish the abovementioned object by moulding a slab in a shallow tilttable mould having one or more removable sides whereby the mould with the formed slab may be tilted from a horizontal or other convenient moulding position to a vertical position and when the lower side of the mould is removed the slab is placed above a foundation and connected to other slabs similarly formed and erected to form a single or cavity wall structure.

The moulds can be employed singly or two or more may be secured within a clamping frame when slabs of large size are to be formed. The mould or group of moulds is or are provided with removable sides and ends and one or more of the sides and ends may be unfastened from the mould or moulds and be provided with members inserted or moulded into the concrete whereby the formed slabs with one or more of the said side and/or end pieces may be erected adjacent to each other above a foundation and the said sides or end pieces utilized for securing struts, tie beams or like temporary supporting members thereto while the building is in course of erection. The sides of the moulds can be shaped to form longitudinal grooves or recesses in the vertical edges of a slab whereby when the side pieces are removed reinforcing members projecting from adjacent slabs can be connected and the spaces therebetween filled with cement or concrete to firmly lock the slabs together.

A salient feature of the invention resides

in the provision of means for supporting the moulds whereby they can be tilted and raised or lowered to facilitate the placing of a slab correctly in position above a foundation.

The moulds can be designed to shape the slabs into a form that will ensure them having a minimum of weight or thickness with a maximum of strength and provision can be made in moulding the said slabs for enabling linings of wood, fibro-cement, plaster or the like to be conveniently attached to the faces thereof.

In order that the invention, the object and nature of which have been set forth, may be readily understood, reference will now be had to the accompanying sheets of explanatory drawings, wherein:—

Figure 1 is a view in perspective illustrating one form of mould and supporting means constructed in accordance with the invention. In this view the mould and supporting means are shown located within a space surrounded by wall foundations upon portions of which slabs are molded to form wall sections.

Figure 2 is a view in sectional side elevation of a mould and the means for supporting the same.

Figure 3 is a view in sectional elevation of a slab shaped by a mould and placed in position on the foundation.

Figure 4 is a view in elevation of portion of a cradle forming part of the supporting means for a mould viewed in the direction of the arrow 4 shown in Figure 2.

Figure 5 is a view in plan of a mould and cradle, portions of the mould being shown removed to clearly illustrate constructional details thereof.

Figure 6 is a view in section of the mould and one supporting member taken on the dotted line 6—6 of Figure 5.

Figure 7 is a view in section of part of a mould filled with concrete, and clearly illustrates a slight modification which hereinafter is fully described.

Figure 8 is a view in section of the upper part of a mould with portion of a slab therein.

Figure 9 is a view in sectional elevation taken on the dotted line 9—9 of Figure 2.

Figure 10 is a view in plan of portion of a

cavity wall and portion of a division wall constructed in accordance with the invention.

Figure 11 is a view in sectional plan showing a detail of the invention which herein-after will be fully described.

In these drawings the reference numeral 10 designates stands comprising pairs of vertical members 11 and long base members 12. A pair of jaws 13 extend upwardly from the vertical members 11 and pivotally supported therebetween is a lever 14 having its long or power arm normally secured as by a pin 15 passing through a hole or holes in standards 16 fitted to the base.

The end of the work arm of the lever is pivotally mounted as at 17 on a supporting cradle. The cradle comprises a pair of longitudinally disposed beams 18 and transverse beams 19. The transverse beams can be arranged in pairs and the power arms of the levers 14 preferably are pivotally mounted between each pair of transverse beams and at about the centre thereof.

It will be understood from the foregoing description that the cradle is free to pivot on the ends of the levers and in order to maintain the said cradle in a horizontal position when the levers are locked against movement links 20 or like devices are employed to connect one edge of the cradle to the power arm of the levers.

In the drawings the links 20 are shown pivotally connected to the transverse bars 19 of the cradle and the free ends of the links are provided with a series of holes 21 adapted to take pins 22 for securing the links to the levers (see Figures 2 and 9 of the drawings).

The ends of the longitudinal or side beams 18 of the cradle are provided with upwardly extending hook members 23 whereby when a series of trays 24 are placed on the cradle they can be forced closely together by driving wedges 25 between the upwardly projecting hook members on one end of the beams and a batten 26 which forms a detachable side for the mould.

A batten 27 is inserted between the upwardly projecting hooks on the opposite end of the beams 18 and the adjacent tray and the upwardly projecting portion of this batten forms the second detachable side of the mould.

Each tray comprises a pair of side rails 28 approximating in length to the height of the wall to be formed and connected by cross members 29 situated near the ends thereof.

The bottom of the trays may be covered by boards or by metal sheeting 30 fitted to the upper faces of the longitudinal and transverse rails and having transverse grooves or corrugations 31 formed therein. Those portions of the tray which are situated between the transverse members 29 and the ends are made deeper than the intermediate portions

and one of the ends of the longitudinal members is provided with upwardly extending brackets 32, which serve to locate and support a batten 33 closely against the upper ends of the trays to form the top of the mould.

The end batten 34 is detachably secured against the lower end of the mould by means of hook shaped catches 34' and the upper end batten is retained in position by means of nails 35, screws or like fastening devices which are inserted through holes 36 in the upwardly projecting hook shaped brackets 32.

If preferred the trays can be constructed entirely of sheet metal pressed into a desired shape with or without a reinforcing frame.

In proceeding to erect a wall the foundations 37 of the buildings are laid in the usual way and the upper surfaces thereof are made quite level. The stands 10 for the cradle are then placed in position within the room area bounded by a foundation and the levers carrying the cradle are connected thereto. It will be obvious that the stands can be located on the outside or inside of a building as desired or found most convenient in practice.

When the levers have been pivotally mounted on the stands the cradle is connected thereto and retained in a horizontal or other convenient moulding position by connecting the links 20 to the said levers by means of the pins 22.

The trays are then placed on the cradle with the depending hook shaped members 38 thereon engaging the upper longitudinal beam 18. The hook shaped members are disposed on the cradle in such a position as to cause the centre of gravity of the completed mould to be disposed approximately about the pivot connections with the power arms of the levers.

The trays may be spaced apart by intermediately disposed battens 39, which are of less depth than the height of the side rails 28 between the transverse members 29 of the trays. The spacing battens may, if desired, be permanently secured to the trays.

When the trays have been placed in position on the cradle the side battens 26 and 27 are inserted between the outmost trays and the upwardly projecting hooks 23 and the upper and lower end battens 33 and 34 are placed in position. The trays and spacing battens 39 are drawn tightly together by inserting the wedges 25 between the upwardly extending hook-shaped brackets on the ends of the longitudinal members on the cradle and the adjacent side batten of the mould.

After a layer of concrete has been placed in the mould longitudinal reinforcing rods 40 may be inserted in the recesses 31 in the bottom thereof and these reinforcing bars may extend through holes 41 in the battens 26 and 27 forming the sides of the mould.

In addition to or in lieu of the reinforcing

bars above described mesh or wire netting reinforcements (indicated at 42 in Figure 7) may be placed on the bottom of the trays prior to filling the mould with concrete or plaster.

5 After the concrete or other building material has been placed in the mould the upper surface thereof is levelled off and made smooth by means of float bars or other approved devices and the concrete is allowed to set.

15 When the concrete has partially set the mould can be tilted to such an extent as to enable its lower edge to rest upon a stool or other support whereby excessive strain will be removed from the cradle and mould, as when large slabs are being formed.

20 When the concrete has set hard the lower end batten 34 is removed by unfastening the hooks 34' and forcing it away from the ends of the trays and by releasing the work arms of the levers from the standards 16 the mould after being swung into a vertical position can then be lowered on to the foundation, (see Figure 2 of the drawings).

25 When the mould has been lowered into position on the foundation and suitably braced the wedges 25 are knocked out to release the sides of the mould and free the 30 cradle. The levers 14 are then raised to move the cradle downwardly out of engagement with the hook shaped brackets 32 on the undersides of the trays when the stands 10 and the cradle are free to be moved away from the erected slab.

35 After the stands 10 and cradle have been moved away from the slab the nails 35 are withdrawn and the trays and spacing battens 39 and prized away and after being cleaned can be used to form another slab.

40 It will be understood that the supporting stands 10 are placed in position to support the cradle and mould when re-assembled alongside of the erected slab whereby when the second slab is formed it may be tilted into position and erected on the foundation alongside of the first mentioned slab.

45 When two or more slabs have been erected above the foundation the spaces between the adjacent vertical edges thereof are filled with concrete or grouting and when this concrete or grouting has set the sections of the wall will be securely connected to each other and a water proof joint ensured.

50 When the reinforcing wires 40 project beyond the sides of the slabs they can be twisted together prior to filling the space with grouting thereby serving to give additional rigidity to the structure.

55 In some instances the slabs may be placed close together and the joints therebetween may be covered with wood or metal battens which are left permanently in position. The slabs when erected may be connected by temporary supporting members nailed to the bat-

tens 33 secured to the upper edge thereof and these battens also serve as top wall plates to which rafters are easily secured. The upper end battens 33 are anchored to the tops of the slabs by bent nails 33', pieces of wire or the like which are embedded in the concrete as shown in Figure 8.

60 If desired battens 43 can be placed in the body of the mould as upon the intermediately disposed spacing battens 39 and these battens may be provided with upwardly projecting pieces of wire or nails 44 adapted to anchor them to the face of the concrete slab (see Figure 7) whereby linings of wood or fibrocement (not shown) can be readily affixed to the walls after the same have been erected. If desired sections of the battens 43 and of the slab at the sides thereof can be removed to provide a free circulation of air in the space between the inner lining and the concrete slab.

65 Alternatively the ribs on the inside of the slabs can be formed of breeze concrete whereby linings can be readily secured thereto by nails, screws or other fastening devices.

70 The linings can be secured by bolts, rivets or like members moulded into the slabs and having portions projecting therefrom and adapted to be inserted in holes in the lining or in straps covering the joints thereof.

75 In the right hand side of Figure 7, a bolt 38' is shown having its threaded end supported in a plastic substance in a hole 39" formed in a spacing batten 39 whereby the head of the bolt is securely anchored in the slab during the moulding operation.

80 The protruding ends of the bolts 39' can pass through holes in the lining or through covering strips or straps and the latter are retained in position on the slab by means of nuts fitted to the bolts.

85 The ribs on the inside of the formed slab ensures a requisite degree of strength and also facilitate the application of a coat of plaster or other lining to the inside of the wall when this is required.

90 When doors, windows or other openings are made in the slabs they may be formed by placing frames as 45, blocks or the like in position on the mould so as to prevent concrete entering the space enclosed thereby. The frames can be retained in position during moulding operations by any approved means.

95 In Figures 5 and 6 of the drawings a frame is shown which is adapted to leave a door opening in the slab and this frame may be removed after the slab has set and has been placed in position on the foundation.

100 The frame may be laid on the bottom of the mould and the slab formed therearound whereby the said frame will be securely anchored in the slab and erected therewith.

105 The doors or window sashes can be mounted in their respective frames before the said frames are placed in the mould.

The bottom of those trays 24 which are adapted to support the frames may be made perfectly flat to ensure an even thickness of concrete around the said frames.

5 When large slabs are being formed the base of the stands 10 for the cradle may be weighted to counterbalance and prevent movement of the same when the slabs are being tilted to be placed in position on the foundation.

10 Alternatively, the base may be extended through openings in the foundation as illustrated in Figure 1 or they may be located above the foundation and suitable openings provided in the bottom edge of the slabs whereby the openings will fit over the extensions of the base of the stands.

20 When the openings are formed in the lower edges of the slabs to accommodate the extension on the base of the stands they may be filled with concrete after the said stands have been removed or these openings may be retained for ventilating purposes.

25 In adapting the invention to the formation of a hollow wall, that is, walls having an internal cavity, the outer wall sections can be erected first as previously described and the inner wall sections are then erected by placing slabs on the foundation at a suitable distance therefrom. Alternatively the inner wall section can be erected before the outer wall section.

30 The inner slabs may be of the same thickness or thinner than the outer slabs and the inner and outer wall sections can be connected by wall ties (not shown) secured within the grouting between the two adjoining sections of the slabs or in any other approved way.

35 If preferred the slabs of the outer wall section 47 can be made quite plain as shown in Figure 10 and their edges can be formed with grooves 46 whereby when two slabs are erected close to each other grouting or cement can be poured into the space therebetween to 40 make a strong joint. The joint between the edges of adjacent slabs can be strengthened by twisting together the projecting ends of reinforcing rods prior to pouring the grouting.

45 The inner wall section 48 may be made and erected as hereinbefore described and the projecting ends of the reinforcing rods 40 are twisted together as at 49 prior to pouring grouting between the joint. When a division wall 49 is arranged in line with a joint between the slabs of an outer wall the projecting ends of the reinforcing bars can be twisted around the bars connecting the outer wall sections thereby forming tie bars (as 50) 50 which serve to strengthen the connection between the division wall and outer wall and retain the outer and inner wall sections 47 and 48 at a desired distance apart.

55 In those cases where a division wall is not disposed in line with the joints in an outer

wall the reinforcing wires at the joints are connected by wire wall ties as hereinbefore described.

In Figure 1 of the drawings each wall is shown composed of a single slab but it will be obvious that the slabs can be of any desired width and two or more separate slabs can be employed to form a wall.

70 If desired the longitudinally disposed reinforcing members may be dispensed with and the adjacent slabs of a wall or fence may then be connected by grouting or concrete poured into suitably arranged moulds 51 (see Figure 11 of the drawings).

75 In order to prevent the grouting uniting with the ends of the slabs, thereby hindering their contraction when setting, the said ends may, prior to the insertion of the concrete or grouting, be given a coating of oil, grease or the like.

80 When erecting fences or boundary walls in this manner, a hole may be formed in the ground immediately below the gap between adjacent slabs, so that the concrete or grouting, when poured, passes thereinto and serves 85 as a post as well as a connecting member.

85 It will be obvious that, if desired, the mould 51 may be arranged so that one or both surfaces of the concrete or grouting will be flush with the adjacent faces of the slabs.

90 Whilst I have described in the foregoing specification certain practical embodiments of the invention and method employed in forming and erecting concrete walls therewith, it will be obvious that various modifications may 95 be made in the construction of the apparatus and method of operation without departing from the spirit and scope of the same and, I therefore, do not wish to be understood as limiting myself by the positive terms employed 100 herein.

105 I claim:—

1. Apparatus for moulding and erecting slabs of concrete in forming wall structures comprising a shallow tiltable mould having 110 removable sides, one or more stands or supports carrying pivoted supporting levers, pivotal connections between the work arms of the levers and the mould, and means for securing the levers and the mould in a fixed position during the moulding operation.

115 2. Apparatus for moulding and erecting slabs of concrete in forming wall structures, comprising a shallow tiltable mould, removable sides and ends on the mould, levers connected to the mould and pivotally mounted on fixed stands or supports, means for retaining the mould in a position for moulding a slab therein, and means for firmly anchoring one of the ends of the mould to the slab to 120 form a top wall plate.

125 3. Apparatus for moulding and erecting slabs of concrete in forming wall structures, a plurality of supporting stands having levers pivoted thereto, a cradle pivotally supported 130

on the work arms of the levers, means for securing the levers in fixed positions on the stands, a plurality of trays detachably secured to the cradle, means for detachably securing side battens between the trays and the ends of the cradle and for clamping the trays closely together, means for securing battens to the upper and lower ends of the trays, and means for retaining the cradle in a horizontal position during moulding operations constructed and arranged whereby the trays can be tilted to place a formed slab in a vertical position above a foundation.

4. Apparatus for moulding and erecting slabs of concrete in forming wall structures consisting of a plurality of stands, levers pivoted to the said stands, a cradle pivotally supported on the work arms of the levers, means for securing the levers in a fixed position on the stands or supports, members for connecting the cradle to the levers or to the supports for retaining it in a horizontal position, trays detachably mounted on the cradle, hook shaped brackets on the cradle and wedges for retaining the trays correctly in position on the cradle, hook shaped brackets on the upper ends of the trays for securing a top plate along the upper edges of the trays, a batten detachably secured to the lower edges of the trays, said trays and battens and top plate constituting a mould for a slab.

5. In apparatus for moulding and erecting slabs of concrete in forming wall structures, a cradle, a plurality of pivotally mounted levers supporting said cradle, a plurality of trays detachably secured to the cradle, detachable ends and sides secured to the tray and forming therewith a shallow mould, transverse grooves in the trays, and holes in the sides of the trays adapted to accommodate reinforcing bars disposed longitudinally in the recesses or corrugations in the trays.

6. Apparatus for moulding and erecting slabs of concrete in forming wall structures, comprising a plurality of fixed supports adapted to be located adjacent to a wall foundation, levers pivotally mounted on the supports, a cradle pivoted to the work arms of the levers, means for detachably connecting the levers to the cradle whereby it will be retained in a horizontal position, a plurality of trays having depending hook shaped members adapted to engage one side of the cradle, upwardly projecting hook shaped members on the ends of the cradle, side battens disposed between the hook shaped members and the sides of the trays, wedges for securely clamping the said battens to the trays and for retaining the trays closely together, a batten secured detachably to the lower ends of the trays, a top plate detachably secured to the upper ends of the trays, and means in the bottom of the tray and in the side battens for accommodating longitudinally disposed reinforcing members.

7. Apparatus according to claim 5 wherein in one of the sides of the mould constitutes a top plate having nails or wires projecting inwardly therefrom whereby the top plate will be securely anchored to a slab moulded on the frame.

8. Apparatus for moulding and erecting slabs of concrete according to claim 5, wherein in spacing battens are interposed between the trays on the cradle and said battens are of less depth than the sides of the tray.

9. In apparatus for moulding and erecting concrete slabs according to claim 5, recesses in the mould and holes in the moulding faces of the members forming the recesses adapted to temporarily receive the ends of fastening members, whereby when a slab is formed in the mould the upwardly extending portions of the fastening members will be anchored therein and the portions temporarily received in the holes will be left projecting from the face of the slab.

In witness whereof I hereunto affix my signature.

THOMAS WALKER FOWLER.
